UNITED STATES PATENT OFFICE

ORA NORCROSS TURNER, OF TEMPLETON, MASSACHUSETTS, ASSIGNOR TO BAY STATE METAL WHEEL COMPANY, OF EAST TEMPLETON, MASSACHUSETTS, A CORPORATION OF MASSACHUSETTS.

FOLDING CARRIAGE.

No. 890,253.

Specification of Letters Patent.

Patented June 9, 1908.

Application filed October 4, 1907. Serial No. 395,912.

To all whom it may concern:

Be it known that I, ORA NORCROSS TURNER, of Templeton, in the county of Worcester and State of Massachusetts, have 5 invented certain new and useful Improvements in Folding Carriages, of which the following is a specification.

This invention relates to baby carriages or perambulators so-called, adapted to be folded 10 into compact form when not in use, and particularly to that class of folding perambulators in which two wheel-carrying frames are hinged or pivoted to the seat-supporting frame, each wheel-carrying frame extending 15 lengthwise of the carriage, and being adapted to be retracted by swinging inwardly under the seat frame, and to be projected by swinging outwardly from the seat frame into position for use.

20 The invention has for its object to provide improved means for swinging the wheel-carrying frames to project and retract the same, and improved means for locking the wheel-carrying frames when they are in their 25 projected or operative positions.

The invention consists in the improvements which I will now proceed to describe and claim.

Of the accompanying drawings, forming a 30 part of this specification,—Figure 1 represents a side elevation of a perambulator embodying my invention, in its extended position ready for use. Fig. 2 represents a side elevation showing the perambulator 35 folded. Fig. 3 represents a section on line 3—3 of Fig. 1. Fig. 4 represents a fragmentary perspective view illustrating the chief novel parts of the structure. Fig. 5 represents a fragmentary sectional view. 40 Fig. 6 represents a fragmentary end elevation looking from the rear end of the carriage. Fig. 7 represents a partial side elevation 45 showing a modification.

The same letters of reference indicate the same parts in all the figures.

In the drawings *a* represents the main or seat-supporting frame of a folding carriage, to which is affixed the seat *a'*. The frame preferably includes two longitudinal parallel 50 side bars *a²*, shown in cross section in Fig. 3, and suitable connecting cross bars *a²⁰*. The end portions of the frame are provided with downwardly-projecting arms *a³⁰* to which are connected by pivot bolts *b*, two wheel-supporting frames *c*. Each wheel-supporting 55

frame is preferably composed of flat metal bars, which include a longitudinal member *c'* extending substantially parallel with the seat-frame, and brackets *c²* projecting downwardly from the longitudinal member *c'* 60 when the carriage is extended for use, said brackets having eyes or sockets which engage axle arms *d*, on which the wheels *d'* are journaled. The pivot bolts *b* are substantially in alignment with the longitudinal bars 65 *c'*, the arrangement of the said parts being such that each of the wheel frames is adapted to stand in a plane substantially at right angles with the seat frame when the carriage is in its operative adjustment, as shown in 70 Fig. 1, and is adapted to be swung inwardly toward the seat frame, so that the carriage may be folded, as indicated in Fig. 2.

Each of the longitudinal bars *c'* is provided with a spiral inclined plane *c³*, which in this 75 embodiment of my invention is formed by imparting a quarter twist to the flat bar *c'*, as clearly shown in Fig. 4. This spiral inclined plane is in effect a screw, which cooperates with a member which is adapted to 80 slide on the bar *c'*, and is in effect a nut which when moved upon the screw portion *c³*, causes a quarter rotation of the longitudinal bar *c'*, and thus acts to swing the wheel-supporting frame about one-quarter of a complete 85 rotation, the arrangement being such that the movement thus imparted to the wheel supporting frame is sufficient to move it from the operative position, shown in Fig. 1, to the inoperative position shown in Fig. 2, 90 when the nut is moved in one direction, and from the folded position shown in Fig. 2, to the operative position, shown in Fig. 1, when the nut is moved in the opposite direction. The nuts on the two cross bars *c'* are connected to move in unison, the preferred construction and connection of the nuts being as 95 follows:

e e represent metal yokes, formed by bending a blank of flat metal into an inverted U- 100 shape, the yokes bestriding the longitudinal bars *c'*, as shown in Fig. 4, the connecting or neck portions of the yokes bearing on the flat sides of the bar *c'*, while their end portions project across the edges of said bars. 105

e² represents a cross bar, which extends from one yoke *e* to the other, the end portions *e³* of said bar passing through orifices formed for their reception in the end portions of the yoke *e*, and bearing against the 110

flat under sides of the bars c' . The nuts thus formed are adapted to slide freely upon the bars c' , and conform so closely to the cross section of said bars that each nut in moving upon the screw portion c^3 , will impart a partial rotation to the bar c' and the wheel frame of which it forms a part. Means are provided for moving the said nuts in unison, the preferred means being two levers f,f , 10 pivoted at f' to ears g affixed to the seat-supporting frame, and links h,h connecting the shorter arms of said levers with the ends e^3 of the cross bar e^2 . When the levers f are moved from the position shown in Fig. 1 to 15 that shown in Fig. 2, they move the nuts upon the screw portions of the wheel frames, and thus swing the wheel frames inwardly to their retracted position. When the levers are moved backwardly from the position 20 shown in Fig. 2 to that shown in Fig. 1, the nuts travel in the opposite direction along the screw portions c^3 , and thereby cause an outward swinging or projecting movement of the wheel frames to their operative position 25 shown in Fig. 1.

The described movements of the levers f are preferably effected by means of a handle i , which is U-shaped, and pivoted at its ends i' to ears j on the rear end of the seat-supporting frame. The handle is connected with the longer arms of the levers f by arms k , which are pivoted at k' to the handle, and at k^2 to the longer arms of the levers f . It will be seen by a comparison of Figs. 1 and 2 30 that when the handle is swung forward over the seat frame to fold the carriage, it causes the above-described action of the lever f , in retracting the wheels, and when the handle is swung back to the position shown in Fig. 1, 35 it causes the described action of the levers f in projecting the wheels.

The screw portions c^3 have different longitudinal adjustments, as indicated in Fig. 4, so that the nut on one of the bars c' acts on 40 the corresponding screw before the co-operation of the other nut and screw commences. The object of this arrangement is to cause the wheel frames to be retracted and projected successively, the wheel frame on one side 45 being folded inwardly before the wheel frame on the opposite side, so that there is no conflict between the two wheels when they are being retracted, the same general statement being true of the outward swinging or projecting movement of the wheel frames.

m,m' represent toggle links which are jointed together at m^2 , the link m being jointed at m^3 to the handle i , while the link m' is jointed at m^4 to the arm k . When said links 50 are in alinement with each other, as shown in Fig. 1, they constitute a brace or strut, which locks the handle i , the levers f and the nuts connected therewith, with the wheel frames in their projected position, so that the 55 carriage cannot be folded and the wheel

frames retracted, until the links m,m' are thrown out of alinement with each other, as shown in Fig. 2.

The described screw and nut mechanism for retracting and projecting the wheel frames, is extremely simple and compact in construction, and efficient in operation. I do not limit myself, however, to the details of the said screw and nut mechanism here shown, it being obvious that any construction whereby the wheel frames are provided with spiral inclined planes or screws with which are engaged slidable nuts connected with operating mechanism on the seat frame, will be no departure from the spirit of my 75 invention. 80

The carriage may be provided with a suitable back o , a foot rest p and other parts which may be necessary or desirable to carry out the purposes for which the carriage is intended. I do not describe said parts in detail, because they are not claimed herein as new or as necessarily connected with the present invention. 85

It will be seen that the links h connecting 90 the levers f with the nuts on the wheel-carrying frames, are adapted to swing vertically when the levers are moved in the folding and opening movements of the carriage, the links being pivoted at their ends both to the levers f and to the nuts. The links therefore constitute a flexible indirect connection between the levers and the nuts, and permit the levers and the portions of the seat frame a with which they are connected, to move vertically independently of the nuts and wheel-carrying frames. The seat-carrying frame may therefore be made of resilient construction, so that its side bars a^2 may constitute 95 springs which give an easy motion to the 100 seat, the seat being adapted to rise and fall by the flexure of the side bars of the seat-supporting frame without in any way interfering with the connection between the levers f and the nuts. The ears a^30 at the rear end 110 of the seat-supporting frame are preferably connected with the central portion of the rear end of the frame, as shown in Fig. 6. The ends of the rear end cross bar of the seat-supporting frame overhang the ears a^30 , as 115 shown in Fig. 6, and are resilient so that they yieldingly support the rear ends of the side bars a^2 . Provision is thus made for giving the seat a desirable spring support entirely by the construction of the frame a , no separate springs being required. 120

In Fig. 7 I show the side bars of the handle provided with extensions i^3 projecting below the pivots i' which connect the handle bars to the ears j , said extensions i^3 being connected by links h' with the ends e^3 of the cross bar e^2 , so that movement is communicated to the nuts directly from the handle, instead of through the agency of the arms k and levers f , the action of the nuts on the 125 130

screws being the same as that already described. In this embodiment of the invention, the side bars of the handle are the equivalent of the levers *ff* in the organization shown in Fig. 1. Each of the described embodiments of the invention, therefore, has levers fulcrumed on the seat frame, and adapted to swing thereon, and means for imparting swinging movements from the levers 10 to the wheel frames for the purpose of retracting and projecting the latter

I claim:

1. In a folding carriage, the combination of a seat-frame, wheel-carrying frames pivoted thereto, and adapted to swing laterally to retract and project the wheels, each wheel-carrying frame having a screw, and means connected with the seat-frame for acting on the said screws to retract and project the 20 wheels.

2. In a folding carriage, the combination of a seat-frame, wheel-carrying frames pivoted thereto, and adapted to swing laterally to retract and project the wheels, each wheel-carrying frame having a screw, nuts movable on said screws to retract and project the wheels, and means carried by the seat-frame for moving said nuts.

3. In a folding carriage, the combination of a seat-frame, wheel-carrying frames pivoted thereto, and adapted to swing laterally to retract and project the wheels, each wheel-carrying frame having a screw, levers fulcrumed on the seat-frame, and nuts connected with the said levers and movable on the screws to retract and project the wheels.

4. In a folding carriage, the combination of a seat-frame, wheel-carrying frames pivoted thereto, and adapted to swing laterally to retract and project the wheels, each wheel-carrying frame having a screw, levers fulcrumed on the seat frame, nuts adapted to engage said screws to retract and project the wheels, and links connecting the nuts with 45 the levers.

5. In a folding carriage, the combination of a seat-frame, wheel-carrying frames pivoted thereto, and adapted to swing laterally to retract and project the wheels, each wheel-carrying frame having a screw, levers fulcrumed on the seat-frame, nuts connected with the levers and movable by the latter on the screws to retract and project the wheels, and means for locking said levers with the 55 nuts in their wheel-projecting position.

6. In a folding carriage, the combination of a seat frame, wheel-carrying frames pivoted thereto, and adapted to swing laterally to retract and project the wheels, each wheel-carrying frame having a screw, levers fulcrumed on the seat frame, nuts connected with the levers, and movable by the latter on 60

the screws, to retract and project the wheels, a handle pivoted to the seat frame, arms pivoted at their end portions to the handle 65 and to the levers, and toggle links connecting the handle with the arms, and adapted to lock the handle arms and levers, with the nuts in their wheel-projecting position.

7. In a folding carriage, the combination 70 of a seat frame, wheel-carrying frames pivoted thereto, each having a longitudinal member which is twisted to form a screw, a cross bar having yokes on its end portions, the said yokes and end portions forming nuts 75 which embrace said members, and are movable thereon, levers fulcrumed on the seat frame, and links connecting the levers with said cross bar.

8. In a folding carriage, the combination 80 of a seat frame, wheel-carrying frames pivoted thereto, each having a screw, nuts movable on said screws to retract and project the wheels, and means for moving said nuts, the relative arrangement of the screws and the 85 nuts being such that the wheel frames are retracted and projected successively.

9. In a folding carriage, the combination 90 of a seat frame, wheel-carrying frames pivoted thereto, each having a screw, nuts movable on said screws to retract and project the wheels, and means for moving said nuts, the screws having different longitudinal positions, while the nuts are in transverse alignment, whereby the wheel frames are retracted and 95 projected successively.

10. In a folding carriage, the combination of a seat frame of resilient construction, wheel-carrying frames pivoted thereto, each having a screw, nuts movable on said screws 100 to retract and project the wheels, levers pivoted on the seat-supporting frame, and flexible connections between the levers and the nuts, whereby the seat-supporting frame is adapted to spring vertically independently of the 105 nuts and wheel-carrying frame.

11. In a folding carriage, the combination 110 of a seat frame of resilient construction, wheel-carrying frames pivoted thereto, each having a screw, nuts movable on said screws to retract and project the wheels, levers pivoted on the seat-supporting frame, and links pivoted to the lower ends of said levers and to the said nuts, said links being adapted 115 to swing vertically, and to permit a vertical movement of the seat frame and levers independently of the nuts and the wheel-carrying frames.

In testimony whereof I have affixed my signature, in presence of two witnesses.

ORA NORCROSS TURNER.
